SASH HANGER

Cecil F. Arens, South Bend, Ind.

Application December 13, 1946, Serial No. 716,111

4 Claims. (Cl. 16—172)

1

This invention relates to fasteners for sash and more particularly to fasteners for screens and storm windows.

It is an important object of the invention to provide a fastener for sash which can be readily secured to the inside of the sash and which is formed to cam the sash into position in a frame.

A still further important object of the invention resides in the provision of a fastener for sash formed with an exterior cam surface for coacting with an element projecting from a frame for guiding said element into engagement with said fastener to thereby hang the sash from the frame.

Another object of the invention is to provide a fastener for sash which enables a person positioned on either side thereof to hang or remove the sash.

A more important object of the invention resides in the provision of a fastener for sash formed to draw a sash toward a window frame and to yieldably hold said sash relative to said frame.

A yet further object is to provide a fastener for a sash which fastener is formed to engage a supporting element projecting from a frame to thereby releasably lock the sash in a swingable position subject to disengagement of the supporting element from the fastener when the sash is rotated about said support as a pivot.

An important object of the invention resides in the provision of a fastener for sash constructed of a single piece of stamping material.

An object of the invention resides in the provision of a fastener for sash wherein the fastener is provided with a plurality of cam surfaces constructed and arranged to coact with an element projecting from a window frame to guide the projecting element into engagement with the fastener and to yieldingly hold the sash in contact relationship with the frame.

A very important object of the invention is to provide a fastener for sash simple in construction and economical to manufacture.

The above and other objects and features of the invention will be apparent from the following description of the device taken in connection with the accompanying drawings which form a part of this specification and in which:

Figure 1 is a sectional view through the top of a window frame showing the device of the invention mounted on a sash and holding the same into position against the window frame;

Figure 2 exemplifies the device of the invention in coacting relationship with a projecting pin or element secured to a window frame and about to be cammed into engagement with the device;

Figure 3 illustrates the manner in which the device of the invention suspends the sash after engagement of the device with a projecting element secured to a window frame;

Figure 4 is a view in perspective as seen from

2

the inside of a house depicting the mounting arrangement of the device of the invention on a sash;

Figure 5 shows a set of stampings from which the fastener is made; and

Figure 6 is a modified form of the device of the invention shown mounted on a sash about to be disengaged from a projecting pin.

Referring now to Figure 1 the reference numeral 10 designates a frame for a window 12 with which a secondary window or storm sash 14 is to be used. Instead of a secondary window such as storm sash 14, the closure member may be a screen sash or the like. The window frame includes an upper casing 16, side casing 18, upper blind stop 20, side blind stop 22, upper jamb 24 and side jamb 26, all of which are properly joined together and arranged to receive the window 12 and the closure member or storm sash 14.

For positioning the sash 14 in the frame a pair of fasteners 30, see Figure 4, are mounted on the inside of the sash at the top for engagement with means such as projecting pins 32, which are screwed or otherwise fastened to the side blind stop 22. Figure 5 exemplifies the preferred embodiment of fastener which is made from two blank strips of metal O and K, the former strip comprising a back member 34 provided with holes 36 to receive screws 38 to securely hold the fastener to the sash 14. The holes 36 are punched or drilled in a flange 40 which is offset from member 34 so that the holes will be more accessible for inserting the screws 38 when the fastener is completely assembled as best shown in Figure 4. It should be noted that the flange 40 is either on the right or left hand side of the member 34 depending on which side of the sash the fastener is to be used. As indicated in Figure 4, there will be one of each type fastener for a sash. That is, there will be right and left hand fasteners. The member 34 is provided with flanges 44 integral with the member and extending from both sides thereof. These flanges 44 are so disposed relative to the member 34 as to be bent or folded back upon the member to thereby grip or otherwise securely clamp the blank strip or element K for supporting the same in cooperative relationship to the strip O as will be hereinafter described.

The upper end or free end of member 34 is provided with a hook 46 having an exterior cam portion and an interiorly formed vertex or pivot C about which the sash pivots or swings when in the lowered position, shown in Figure 3. This hooked end is formed into a curve with a sweeping arc or large radius in order to furnish a movable pivot or a series of pivot points for the fastener. That is, the use of a hook having a curvature, such as shown, enables the fastener to assume more than one position of pivot along the curvature to permit sliding the sash on the pins away from the frame. This sliding of the sash on the pins normal to the frame might be

described as an in and out movement of the sash relative to the frame. A hooked end, of the shape herein shown, also permits swinging the sash outwardly a considerable distance at the bottom, as is sometimes desirable where a storm sash is used.

The fastener 30 comprises the metal strip or back member K to which the resilient metal strip O, which is preferably made of spring steel or other yieldable material, is suitably attached. 10 The element or metal strip K has one end 50 securely attached to the lower end of said member 34 by the flanges 44 and the other end or free end 52 angularly disposed with respect to the back member and extending beyond the hook 46 15 to be engaged by the projecting pin 32 to help guide the same into engagement with the member 34. The construction and arrangement of element K is such that it will ride against the projecting pin 32 when the sash is raised to the position shown, in Figures 1 and 4, to cam or draw the sash into place and to yieldingly hold said sash in the frame.

To hang the sash it is moved upwardly along the side blind stop so that the portions 46 of the fastener (see Figure 2) engage the projecting pins 32 to thereby guide the fasteners into engagement with the pins. That is, as the sash is moved upwardly the exterior portions 46 of the fastener follow along the projecting pins 32 until the pins engage the ends 38 of the yieldable spring strips K, at which time an additional upward force on the sash causes the ends of the strips to yield so that the fasteners can now be moved into engagement with the pins (see Figure 3). In this position the pins are releasably locked in engagement with the fasteners by strip K. Continued upward movement of the sash causes the resilient elements of the fasteners to slide along the pins to thereby draw the closure or sash into position in the frame against the blind stops.

To remove the sash from the frame when in the position shown in Figure 1, lower the sash by swinging it slightly outwardly at the bottom until the relative position of the projecting pins 32 and the fasteners are as shown in Figure 6 of the modified embodiment, at which time the sash is swung further outwardly so that the inner top edge W of the sash pivots about the side blind stop as a fulcrum. This action causes the ends of the yieldable members to be urged away from the cam portions to disengage the fasteners from the projecting pins.

Figure 6 is a modified embodiment of the invention in which the reference numeral 74 designates a fastener mounted on a screen 75 and made from a single stamping comprising a member 76 provided with holes 77 to receive screws 78 for securely attaching the fastener to the screen or sash. A yieldable element 79 is bent back upon the member 76 so as to have an end 80 extending beyond and in contact with a preformed portion 82 of the member 76. As was explained in the preferred embodiment the preformed portion 82 and the end 80 provide means for guiding the projecting pin into engagement with the fastener. In the modified embodiment the hook-like portion 82 is in the form of an inclined flat surface to thereby provide a cam face to engage projecting pin 32.

While I have shown and described several constructions in which the invention may be advantageously embodied, it is to be understood that the constructions shown have been selected

merely for the purpose of illustration or example, and that various changes in the size, shape, and arrangement of the parts may be made without departing from the spirit of the invention or the scope of the subjoined claims.

I claim:

1. A fastener for a sash comprising a first strip attachable to an inside upper corner of a sash and having its upper end bent outwardly to form a hook, and a resilient second strip attached to the base of the first strip and inclined outwardly from the plane of the first strip, said second strip extending against and beyond the hook of the first strip to guide a pin attached at right angles to a sash frame into the enclosed space between the two strips and to resiliently receive such a pin against the second strip thereby urging the sash inwardly into its frame as the sash is moved upwardly into its frame.

2. A fastener for a sash comprising a back member attachable to an inside upper corner of a sash and having its upper end turned outwardly to provide a hook, and a resilient element attached to the lower end of said member and inclined outwardly therefrom with the free end of said element lying adjacent the hook, said free end of the element extending beyond said hook to guide a pin projecting from a sash frame into the enclosed space between said member and element, said resilient element engaging such a pin to thereby urge the sash inwardly into its frame as the sash is moved into position.

3. A fastener for a sash comprising a back member attachable to an inside upper corner of a sash, said back member having a hook at its upper end inclined at an acute angle to said member, and a resilient element attached to the lower end of said back member and inclined outwardly therefrom with the free end of said element being contiguous said hook and extending therebeyond to guide a pin attached at right angles to a sash frame into the enclosed space between the back member and resilient element, said resilient element engaging such a pin to thereby urge the sash inwardly into its frame as the sash is moved into position.

4. A fastener for a sash comprising a single metal strip formed with a back member to lie against a sash and attachable to an inside upper corner of a sash and having its upper end bent outwardly to form a hook and its lower end bent back on said member at an acute angle thereto to provide a resilient element extending beyond said hook and lying adjacent the end thereof, said resilient element extending beyond said hook to guide a pin attached at right angles to a sash frame into the enclosed space between the back member and resilient element, said element also resiliently receiving such a pin thereagainst to urge the sash inwardly into its frame as the sash is moved upwardly into its frame.

CECIL F. ARENS.
